UNITED STATES PATENT OFFICE.

THOMAS ROLAND WOLLASTON, OF MANCHESTER, ENGLAND.

METHOD OF OPERATING THE CRUSHER ROLLS EMPLOYED WITH GAS PRODUCERS,
FURNACES, AND THE LIKE.

Application filed October 22, 1923. Serial No. 670,029.

To all whom it may concern:

Be it known that I, THOMAS ROLAND WOLLASTON, a subject of the King of Great Britain, residing at 26 Corporation Street, 5 Manchester, in the county of Lancaster, England, have invented certain new and useful Improvements in Methods of Operating the Crusher Rolls Employed with Gas Producers, Furnaces, and the like, of which

10 the following is a specification.

The invention is for an improved method of mechanically operating or rotating the rolls employed with gas producers, furnaces and the like, for crushing and discharging 15 ash and clinker, said invention being applicable for example, to the crusher rolls described in the specification of my British Patent No. 113025, wherein sets of rolls are capable of being independently and selectively controlled as regards their rotation.

The object of the present invention is to arrange for the rolls being capable of alternate forward and reverse motions, such reverse motion being of less extent or extents 25 than the forward movement, by preference. Thus, in the case of the crusher rolls described in the specification of my patent above named where a pair of rolls move inwardly or towards each other by rotating 30 in opposite directions I now arrange for these movements to be reversed at intervals of time, when required. For example, after a roll has had an angular movement of 25 degrees say, it may be stopped and made 5 to move backwards through an angle of 15 degrees say, the first above-mentioned movement taking place when crushing operations are in progress, and the latter or reverse movement taking place when clearing operations are required. The introduction of 40 these movements or extents thereof may be determined by the attendant in charge.

With reference to the accompanying drawings, illustrating a form and application of the invention to a gas producer, and of the kind according to my prior Patent No. 113025 referred to Fig. 1 is a sectional plan, of said producer provided with rolls and gearing for the same, but the present 45 invention is applicable to other arrangements and numbers of rolls. In Fig. 1 aforesaid the rolls indicated have each an opposite roll forming a pair movable adjacent to each other. Fig. 2 on an enlarged 50 scale indicates a pair of the rolls afore-

said assumed to be situated on one side of the producer grate, the gearing for which rolls being in connection with a ratchet and rider-pawl device for enabling the desired opposite movements of a roll or rolls to be 60 accomplished. Fig. 3 is a view at right angles to Fig. 2 and includes additional mechanism for the purpose in view.

a is the producer, and *b*, *b*¹ rolls of a number employed. *c*, *c*¹ are respectively worm wheel and worm forming gearing for a roll *b*, and *c*², *c*³ are respectively similar wheel and worm for an adjacent roll *b*¹ of the pair shown. In Fig. 2 the worm gearing is arranged to give opposite motions to 70 the rolls *b*, *b*¹ on rotation of driving shaft *d* throughout its length. But clutches *d*¹ are indicated, for connection of worms *c*¹, *c*³ with shaft *d*, the putting out of gear of any one of which will result in the corresponding roll being unaffected or incapable 75 of movement.

In the example given, and referring to Figs. 2 and 3, the shaft *d* has keyed to it a pair of ratchet wheels, *e*, *e*¹, the teeth 80 of which are in opposite directions, and loosely mounted on said shaft is a plate device *h*, *h*¹, supporting pawls *k*, *k*¹, which are loosely and suitably mounted on cross shafts or bearing spanning across the gap 85 between said parts *h* and *h*¹. A shaft or spindle *l* attached to the upper parts of *h* and *h*¹, is connected by connecting rod *m* to a pin *n* of a crank upon crank-shaft *o*, the latter assumed to be driven from a 90 suitable source of power. *r* is a rider-plate device for the pawls *k*, *k*¹, which rider-plate is shown in Fig. 3 connected by link *s* to a tumbler lever *t* pivoted at *t*¹ to a fixed pin 95 suitably mounted.

s is shown formed with right and left screw threads and is divided between, so that the operation of sleeve *s*¹ will result in rider-plate *r* being set relative to the pawls *k* and *k*¹ where desired by the attendant.

The tumbler lever *t* is formed with a grooved upper part, along which a movable weight *u* may travel from one end to the other according to the position of said lever 100 *t* after the manner of like tumbler device employed in fuel economizers with boiler plant.

Attached to shaft *d* is a sprocket wheel or the like *k*² connected by positive driving 110

means for example a pitch chain k^3 (Fig. 3) to a second gear wheel k^4 mounted upon and attached to shaft k^5 movable in bearings not indicated. Upon said shaft k^5 is mounted eccentric v , the opposite end of the rod of which is slotted as shown, and engages a pin t^2 on lever t . Stops w projecting from a suitable part of the plant are indicated for restricting the extreme positions of lever t aforesaid.

It will be seen that with the rider plate r set as in the drawings, pawl k^1 is capable of operating ratchet e^1 , while pawl k , resting on the surface of said plate r is placed out of action. But the intermittent movement of ratchet e^1 , through k^2 , k^3 , k^4 and k^5 results in an intermittent movement of the eccentric v so that eventually the slotted end of the rod of the latter pulls upon pin t^2 until the lever t is, as a consequence, moved over the upright position indicated by broken line, when the weight u moves or rolls by gravity to the opposite end of the groove in the lever t . In this way, the lever t is rapidly moved to the other extreme of its position as determined by one of the stops w , and the rider plate r is just as rapidly moved to release pawl k and put k^1 out of action. The oscillatory movement of rod or link m being continuous, now operates through engaging pawl k to rotate shaft d in the opposite direction.

If however one of the clutches d^1 is out of gear, the roll affected is necessarily not reversed in motion by the change above described. This might be desirable in those cases where the teeth of one roll come adjacent to a blank on an opposite roll of a pair. That is to say, under such circumstances, one roll could be stationary and the companion or opposite roll reversed only, when clearing of clinker is desirable.

It is obvious however, that rolls may be reversed in pairs, by omitting the clutches d^1 or like devices, and attaching the worms to shaft d also, by suitable adjustment of the rider-pawl parts shown in Fig. 3, the extent of reverse motion imparted to a roll may be varied, and the degree of forward motion similarly controlled.

In those cases where, instead of a pair of opposite rolls, there is provided a single roll working in conjunction with a fixed

metal plate, and between which roll and plate the clinker is broken, only said roll is required to be capable of forward and reverse motions as described.

It is evident that various means may be adopted for operating or controlling the rider-pawl device or equivalent, which rider I make no claim to per se; also the degrees of forward and relative reverse motions of the rolls whether independently or jointly controlled, may be varied, as well as the design of parts involved.

In Fig. 2, the rolls are arranged to be driven at different speeds of rotation, but they may be arranged to rotate equally, by using equal gear wheels.

I claim:—

1. A gas producer or furnace, pairs of gear-driven clinker crushing rolls therein connected to operative mechanism for alternately and partly reversing the revolutions of rolls in said pairs, connective mechanism automatically controlled for producing said reversals of motion, substantially as herein set forth.

2. A gas producer or furnace, pairs of clinker crushing rolls therein driven by worm and wheel gearing, the worm gearing loosely mounted on controlled revolute shafting, clutches, on said shafting for connecting the same to the worms aforesaid, ratchet wheels attached to said shafting with the teeth of one of a pair in the opposite direction to the teeth of the other of the pair, rider pawls adjacent to said ratchets for being alternately in gear with said ratchets each to each, and for the purpose of driving the shafting aforesaid in the one direction and then in the other, a pivoted frame carrying said rider-pawls and on which they are pivoted, said frame operated by connection to a source of power, a mounted crank or eccentric driven from the shafting aforesaid, a loosely weighted and pivoted tumbler lever, operated by the rod of said eccentric, and for automatically causing first the one and then the other ratchet pawl to be in gear with its respective ratchet wheel, substantially as herein set forth.

In testimony whereof I have affixed my signature.

THOMAS ROLAND WOLLASTON.
